(57) **CLAIM**

I claim, the ornamental design for a wrist brace, as shown and described.

DESCRIPTION

FIG. 1 is a bottom perspective view of the wrist brace; FIG. 2 is a bottom elevational view thereof; FIG. 3 is a top elevational view thereof; FIG. 4 is a first side elevational view thereof; FIG. 5 is a second side elevational view thereof; FIG. 6 is a front plan view thereof; FIG. 7 is a back plan view thereof; FIG. 8 is a bottom perspective view thereof when worn; and, FIG. 9 is a top elevational view thereof when unfolded. The thin solid lines in the views have been provided for the purpose of illustrating the uniformity of the planar surfaces and the contour of the surfaces and are not a claimed surface pattern.

The broken lines in the drawings illustrate the environment of the wrist brace which forms no part of the claimed design.
